ATTORNEYS

UNITED STATES PATENT OFFICE.

JOHN J. HUGHES, OF BROOKLYN, NEW YORK.

COMBINED PEN AND PENCIL.

1,334,860.

Specification of Letters Patent. Patented Mar. 23, 1920.

Application filed July 3, 1919. Serial No. 308,503.

To all whom it may concern:

Be it known that I, JOHN J. HUGHES, a citizen of the United States, and a resident of the city of New York, Bensonhurst, borough of Brooklyn, in the county of Kings and State of New York, have invented a new and Improved Combined Pen and Pencil, of which the following is a full, clear, and exact description.

10 The present invention relates to new and useful improvements in writing implements, and pertains more particularly to a combined fountain pen and magazine pencil.

15 The primary object of the present invention is to provide means by which the writing operation may be carried on either with a lead pencil or with ink.

20 A further object of the invention is to provide a single device in which both a lead pencil and a pen are combined.

With the above and other objects in view, reference is had to the accompanying drawings in which—

25 Figure 1 is a longitudinal sectional view;

Fig. 2 is a view in elevation of the device in the form in which it is used as a pencil;

Fig. 3 is a view in elevation of the device showing the several parts in their respective positions when used as a pen.

Referring more specifically to the drawings, the reference character 5 designates a barrel or ink chamber, said barrel or ink chamber 5 being provided on one of its ends 35 with an external thread 6 and an internal thread 7. The opposite end of the barrel is provided with an external thread 8 and an internal thread 9, the internal thread 9 being carried by the tapered end of the lead 40 receptacle 10, which extends longitudinally of the barrel 5 on its interior as shown. The external thread 8 is formed on the exterior of the barrel 5, and is adapted to form the means by which a tapered head 11 is secured 45 to the barrel 5. This tapered head 11 is provided with an inwardly-projecting portion 12, the opposite sides of which are bifurcated, as at 13, to form a suitable gripping member for the lead, which is designated by the reference character 14.

Secured within the opposite end of the barrel and retained therein by the thread 7, is a head member 15. The head member 15 carries the writing point 16 in any desired 55 manner, said point receiving its supply of ink by means of the feeder 17. The refer-

ence character 18 designates a cap, which is adapted to cover the writing point when the latter is not in use, and when it is desired to use the writing point, said cap is reversed 60 and is retained on the opposite end of the barrel 5 by reason of engagement of its threads 19 with the threads 20 adjacent the opposite end of the barrel.

The operation of the lead pencil is as follows:

The lead 14 is inserted in the head 11, and the projected portion thereof is extended into the receptacle 10. With the parts in this position, the tapered extension 12 is 70 screwed into the tapered recess 21, and owing to the bifurcations 13, the fingers 22 are caused to grip the lead to prevent movement thereof longitudinally of the receptacle 10 and the head 11, and when it is not 75 desired to use the pencil, if the head 11 is rotated sufficiently to loosen the gripping fingers 22, the lead will be freely moved within the receptacle 10 provided therefor, where it may remain until it is desired to 80 again use the same.

From the foregoing it will be apparent that the present invention provides a combined pen and pencil, and said pen and pencil is capable of use as either without any 85 especial modifications of construction.

Having thus described my invention, I claim as new and desire to secure by Letters Patent:

1. A device of the character described 90 comprising a barrel having a reduced screw-threaded end, a lead-carrying chamber within the barrel and integral therewith, said lead-carrying chamber being rigidly connected with the reduced screw-threaded 95 end of the barrel by a tapered internally screw-threaded tubular section, a lead-gripping member adapted to be inserted into the open end of said lead-carrying chamber, and a resilient lead-gripping member 100 adapted for engagement with the internal tapered screw thread of the section connecting the threaded end of the barrel with the lead chamber for causing said resilient lead gripping member to grip the lead and prevent movement thereof relative to the lead-gripping member, said lead gripping member 105 having a screw threaded flange for engagement with the reduced end of the barrel for securing the lead gripping member 110 in operative position.

2. A device of the character described

comprising a barrel having a screw threaded end, an integral lead chamber formed with said barrel and provided at one end with an enlarged tapered internally threaded opening, and lead-gripping means comprising resilient members adapted for engagement with the internally screw-threaded tapered portion of the lead chamber for

causing said resilient members to grip the lead contained within the lead chamber, said lead gripping means having a flange coöperating with the threaded end of said barrel, to retain the lead holder in operative position.

JOHN J. HUGHES.
